ARTHUR WHITTAKER RICHARDSON, OF SHELL HAVEN, THAMES HAVEN, ENGLAND,
ASSIGNOR TO SHELL-MEX, LIMITED, OF LONDON, ENGLAND, A COMPANY OF GREAT
BRITAIN

BURNER

Application filed August 1, 1928, Serial No. 296,762, and in Great Britain August 2, 1927.

In heating lamps commonly in use and having a wick or equivalent device to which oil fuel is supplied, the surface of the wick becomes incrusted with comparatively hard 5 carbon to such an extent as to clog the wick and impair the efficiency of the lamp and prevent proper combustion.

The main object of the present invention is to provide a lamp which will burn for 10 long periods without attention, and in which the wick or equivalent device, shall not become incrusted with carbon.

According to a further feature of the invention, a burner for an illuminating lamp 15 comprises in combination an annular wick, two concentric tubes, the inner of which forms an air supply passage, and the outer of which is formed of a poor conductor of heat, such as glass, and projects above the 20 wick. Preferably the outer tube is outwardly flared at its upper end. Preferably also the inner tube is formed of heat conducting material, such as steel.

In the accompanying drawings which illustrate the invention, Figure 1 is a sectional elevation, Figure 2 is a sectional elevation of a modification and Figure 3 a sectional elevation of a further modification.

Referring more particularly to Figure 1, 30 1 is the body of a lamp having a central tube or liner 2, the space between the body 1 and the liner 2 forming an annular chamber 3 for liquid hydrocarbon which is supplied thereto through a tube 4 communicating with any suitable form of reservoir. 35 5. 6 is an inner tube which can slide freely in the liner 2 and is provided at its lower end with a sleeve nut 7 which screws into the bottom of the body 1. The bottom end of 40 the tube 6 is closed by a cup-shaped sleeve 8 having holes 9 adapted to move into and out of register with similar holes formed in the inner tube 6. The necessary relative movement between the sleeve 8 and tube 6 45 is permitted by a pin 10, secured on the tube 6 which moves in a slot 11 formed in the sleeve 8. 12 is an outer tube formed of glass, carried by a sleeve nut 13 which screws into the body 1. Located between the outer tube 50 12 and the liner 2 is a wick 14 which can

be raised or lowered by a handle 15 having the usual toothed wheel or the like 15^a in engagement therewith. 16 shows a flue leading to a refrigerating apparatus (not shown). 17 is a sleeve which fits into the lower end of the flue 16 and is provided with a flared lower end. The body 1 is provided with a bracket 18 by which the lamp can be secured in position.

It will be seen that in the lamp shown in Figure 1, the following adjustments can be made:—

The amount of air admitted to the inner part of the top of the wick 14 can be regulated by opening or closing the holes 9, 65 while the height of the tube 6 can be adjusted by rotating the sleeve nut 7. The gap between the lower end of the sleeve 17 and the top of the tube 12 can be regulated by rotation of the sleeve nut 13, thereby adjusting the amount of air admitted to the outer side of the top of the wick 14, while the handle 15 enables the wick 14 to be raised or lowered.

In operation, in order to light the lamp, 75 the wick is turned up and the fuel oil on the upper surface of the wick is ignited. As the upper inner periphery of the sleeve becomes heated, the wick is turned down and a heated zone is created on the upper inner periphery 80 of the outer tube. The central air current passing up the inner tube 6 and the outer air current passing between the upper end of the outer tube 12, and the flared end of the sleeve 17, and converging across the wick, 85 form with the vaporized fuel a combustible mixture a short distance away from the wick, so that the wick is not charred by the flame.

The control of the supply of air to the outer side of the wick may, if desired, be effected by providing a chimney coaxial with the tubes and having a sleeve formed with holes adapted to be moved more or less into register with holes formed in the wall of the chimney.

A heating lamp having the dimensions given below, has been found suitable for use with a flue 25 mm. in diameter, employed for

heating the generator of refrigerating apparatus.

An outer tube 24 mm. in diameter, the top of the outer tube being located from 1 to 2 mm. below the bottom of the flue, may be used with a central tube, the top of which is located above the top of the outer tube, preferably at least 2 mm., and may be considerably more, and an annular wick is located between the central tube and the outer tube, the top of the wick being from 1 to 3 mm. below the top of the outer tube. A suitable size for the central tube is 13 mm. diameter and may be made smaller, but should not, as a rule, be less than 8 mm. in diameter. The outer tube is made of a material which is a poor conductor of heat, such as glass or porcelain, and may conveniently be, say, 1 mm. thick.

It may be pointed out that if the parts be dimensioned within the limits enumerated above, they are suitable for most grades of oil commonly used for illuminating lamps. In cases where a supply of oil of a definite standard can be relied on, it is not necessary to provide means for adjustment when once their correct position has been found. In general, however, it is desirable to make the parts adjustable, since slight variations in the quantity of the oil may necessitate adjustment.

In the modification shown in Figure 2, the body 19 of the lamp has a fixed central tube 20, the annular space between the body 19 and the tube 20 forming the reservoir for the liquid hydro-carbon, while the tube 20 serves to admit air to the wick 14'. The flow of air through the tube 20, is controlled by an arrangement similar to that illustrated in Figure 1, i. e. a sleeve 8' having holes 9' adapted to be moved into and out of register with holes formed in the tube 20, and the necessary movement being permitted by the pin 10' secured to the tube 20 and extending into a slot 11' in the sleeve 8'. The outer tube 12' is formed of glass and is outwardly flared. 22 is a spreader of known form, and comprises a perforated cap-like member supported by a shoulder 20' on the tube 20.

The burners shown in Figures 1 and 2, while being very satisfactory as regards affording a suitable source of heat for considerable periods without attention, as a rule emit a noise similar to that emitted by the well known Primus lamp or a brazing lamp employing liquid hydrocarbon as its fuel. In some cases, the noise is not objectionable, but can be obviated by modifying the lamp, as shown in Figure 3.

In this modification, the inner tube 6'' is in effect, formed in two portions 6a and 6b. The portion 6a is fixed while the portion 6b is arranged to extend a considerable distance (say one and one quarter inches) beyond the wick 14'', the extended portion

being provided with perforations 23 to allow the passage of air therethrough. The portion 6b of the inner tube 6'' is fast with a central rod 30, which passes through the fixed portion 6a and is screwthreaded at its lower end, to which end is secured an operating finger knob 31. The screwthreaded portion is in engagement with a nut 32 whereby when the knob 31 is rotated, the rod 30 and with it the portion 6b, is moved axially. If desired, the upper end of the tube 6'' may be provided with a plate 24 having a number of perforations 25, the central one of which is of larger diameter than the remainder. In this modification also, an open ended metal frusto-conical member 27 having perforations 28 is provided and which rests upon a flange or ridge 29 formed on the outer tube 12'', the upper end of the cone normally being approximately level with the top of the inner tube.

In such a modified burner, which has been found to give good results, the inner tube is about $\frac{3}{8}$ " in diameter, and projects a considerable distance, for example, about $1\frac{1}{4}$ ", above the wick, the inner tube being provided with a number of perforations to allow the passage of air therethrough.

The outer tube (when the burner is in operation) projects from $\frac{1}{8}$ " to $\frac{3}{16}$ " above the wick, and the lower end of the cone is 1" in diameter and the flange or ridge on the outer periphery of the outer tube is located, say, $\frac{1}{4}$ " above the top of the container; the upper end of the cone is about $1\frac{3}{8}$ " in diameter, the cone being of such length that its upper end is approximately level with the top of the inner tube.

When it is desired to burn gas, oil or other liquid hydrocarbon having a high flash point, the inner tube 6'' may be formed of metal, preferably a non-scaling metal alloy, in order that the transference of heat from the upper end of the inner tube towards its lower end may assist in the vaporization of the liquid hydrocarbon, the outer tube being, as before, formed of a material which is a poor conductor of heat, such as porcelain or glass.

In operation, in order to enable the burner to be lighted, the wick is raised and the portion 6b of the inner tube 6'' lowered. As the projecting perforated portion of the tube 6'' and the outer periphery of the outer tube become heated, the wick is lowered and the inner tube raised. The heated upper end of the inner tube assists in the vaporization of the liquid hydrocarbon, the space between the inner tube and the cone forming, in effect, a mixing chamber for the vaporized hydrocarbon and air.

A burner constructed in this manner is suitable for heating the flue of a refrigerating apparatus, and is also applicable for use as a stove, and is, moreover, capable of

burning for considerable periods without attention, owing to the fact that in operation the wick is some distance below the top of the inner and outer tube, in which 5 position the top of the wick is comparatively cool; as a result a comparatively long period elapses before the wick becomes charred to any serious extent. A slight incrustation is slowly formed on the top of 10 the outer tube, but this does not materially affect the supply of oil for combustion and can, moreover, be readily removed, if desired.

What I claim is:—

15 1. In a device of the class described, a container for combustible liquid having a combined draft and wick tube with means for admitting air to the lower portion of said tube for passage upwardly there- 20 through, a wick surrounding and contacting the said tube, and an outer tube formed of a material that is an extremely poor conductor of heat, surrounding and contacting the said wick whereby the wick can be locat- 25 ed below the top of the tube when the lamp is alight.

2. In a device of the class described, a container for combustible liquid having a combined draft and wick tube with means 30 for admitting air to the lower portion of said tube for passage upwardly there- through, a wick surrounding and contacting the said tube, an outer tube formed of a material that is an extremely poor conductor 35 of heat, surrounding and contacting the said wick whereby the wick can be located below the top of the tube when the lamp is alight, a perforated tube slidably mounted within the interior of the combined draft and wick 40 tube to receive air therethrough and projecting above the wick to form a continuation of the combined draft and wick tube, and a perforated member surrounding and supported in spaced relation to the third 45 mentioned tube to form a combustion chamber above the wick and between the perforated member and third mentioned tube.

3. In a device of the class described, a container for combustible liquid having hollow draft means for the passage of air upwardly therethrough, a wick surrounding and contacting the said means, an outer hollow means formed of a material that is an extremely poor conductor of heat surround- 55 ing and contacting the said wick whereby the wick can be located below the top of the outer tube when the lamp is alight.

4. In a device of the class described, a combined draft and wick tube having means 60 for admitting air for passage upwardly therethrough, a wick surrounding and contacting the said tube for coaction with a supply of fuel, and an outer tube surrounding and contacting the said wick formed of 65 a material that is an extremely poor con-

ductor of heat, whereby the wick can be located below the top of the outer tube when the lamp is alight.

5. In a device of the class described, a container for combustible liquid having a combined draft and wick tube open at the lower portion for admission and passage of air upwardly therethrough, a wick surrounding and contacting the said tube, an outer tube formed of a material which is an extremely poor conductor of heat surrounding and contacting the said wick whereby the wick can be located below the top of the tube when the lamp is alight, a perforated tube to receive air through the combined draft and wick tube projecting above the latter to form a continuation thereof, means for moving the third mentioned tube axially with respect to the combined draft and wick tube, and a perforated member surrounding and supported in spaced relation to the third mentioned tube to form a combustion chamber above the wick and between the perforated member and third mentioned tube.

In testimony that I claim the foregoing as my invention I have signed my name this 18th day of July, 1928.

ARTHUR WHITTAKER RICHARDSON.
